UNITED STATES PATENT OFFICE.

ERASmus D. LEAVITT, JR., OF CAMBRIDGEPORT, MASSACHUSETTS.

STEAM-CYLINDER FOR STEAM-ENGINES.

SPECIFICATION forming part of Letters Patent No. 402,256, dated April 30, 1889.

Application filed October 12, 1888. Serial No. 287,952. (No model.)

To all whom it may concern:

Be it known that I, ERASmus D. LEAVITT, Jr., of Cambridgeport, in the county of Middlesex and State of Massachusetts, have invented 5 certain new and useful Improvements in Steam-Cylinders for Steam-Engines, of which the following, taken in connection with the accompanying drawings, is a specification.

My invention relates to cylinders of steam-10 engines; and it consists of a novel construction of the ports thereof, which reduces the volume of the waste-space between the valves and the piston at the end of each stroke, thus accomplishing a saving of steam without di-15 minishing the effectiveness of the engine, all as will be readily understood by reference to the description of the drawings and to the claims to be hereinafter given.

Of the drawings, Figure 1 represents a sec-20 tional elevation of a steam-cylinder, its heads and valves, and showing the piston and piston-rod thereof in elevation. Fig. 2 represents an elevation of the upper inlet-chest and port. Fig. 3 represents a sectional ele-25 vation of the same with the valve-seat and valve in position, the cutting plane being on line $x x$ on Fig. 5. Fig. 4 represents a similar view of the same parts with the port shown as it has heretofore been constructed; 30 and Fig. 5 represents a sectional plan of the parts shown in Fig. 3, the cutting plane being on line $v v$ on that figure. Figs. 3, 4, and 5 are drawn to an enlarged scale.

In the drawings, A is a steam-cylinder, pro-35 vided with the upper and lower inlet-chests, A' and A², and the upper and lower exhaust-chests, B and B'. The upper end of the cylinder is closed by the head C, while the lower end is similarly closed by the head D, 40 through which passes the piston-rod E, upon the upper end of which is secured the piston F, in a well-known manner.

From the interior of the cylinder A to the inlet and exhaust chests A' and A², B and B' the 45 ports or passages G communicate.

Within the inlet-chests A' and A², over the ports G, are secured the valve-seats H, pro-50 vided with a series of vertical slots, a a, and outside of this valve-seat H the valve I, pro- vided with corresponding slots, b b, is adapt-

ed to slide to close or open said slots a a, as desired, all in a well-known manner. The exhaust-chests B and B' are similarly pro- vided with valves and valve-seats; but in this case the valve slides between the port G 55 and the valve-seat, all in a well-known manner.

The ports G are made as shallow as pos-50 sible in the direction of the length of the cyl-inder and extend well across the cylinder, as 60 will be seen by reference to Fig. 5, while the slots b b and a a in the valves and valve- seats must be very much deeper in the di- rection of the length of the cylinder, in order 65 that the aggregate area of said slots in the valve or valve-seat shall equal the area of the ports G in the cylinder. Therefore the outer ends of the ports G have been made flaring, 70 as shown in Fig. 4, so that the steam may readily pass through the slots a a and b b 70 and then through the port G into the cylinder without being throttled. This flaring mouth of the port has heretofore extended the en- tire length of the port, which made an en- 75 tirely unnecessary waste of steam, for the reason that the flaring of the mouth of the port G at points immediately behind the par- titions c c in said valves and valve-seats ac- 80 complished no useful result, but simply formed spaces in which the steam would lodge.

It has therefore been found desirable to dispense with these useless spaces, and, instead of making a flaring mouth which ex- tends the whole length of the port G, to sim- 85 plly provide the outer end of said port with as many flaring passages d d as there are slots in the valve-seat H, with which slots said pas- 90 ages communicate, as fully shown in Figs. 3 and 5.

By this construction a considerable volume 90 of waste-space is dispensed with, which re- sults in a great saving of steam.

What I claim as new, and desire to secure by Letters Patent of the United States, is—

1. In a steam-engine, the combination of a 95 valve and valve-seat, each provided with a series of transverse slots or ports, and a cyl-inder having a port or passage made shallow in the direction of the length of said cylinder for the greater part of the distance from its 100

inner to its outer end, and terminating at its outer end in a series of flaring passages corresponding in number and height in the direction of the length of the cylinder to the length of the slots or ports in the valves.

2. A steam-cylinder provided with a shallow passage extending from each steam-chest to the interior of said cylinder and terminating at its outer end in a series of flaring 10 smaller passages, substantially as and for the purposes described.

In testimony whereof I have signed my name to this specification, in the presence of two subscribing witnesses, on this 8th day of October, A. D. 1888.

ERASMUS D. LEAVITT, JR.
